(57) **CLAIM**

The ornamental design for an assembling toy block, as shown and described.

DESCRIPTION

FIG. 1 is a perspective view of an assembling toy block embodying the new design;

FIG. 2 is a top plan view thereof;

FIG. 3 is a front view thereof;

FIG. 4 is a left-hand side view thereof;

FIG. 5 is a sectional view taken along line 5-5 of FIG. 2;

FIG. 6 is another top plan view thereof, showing the toy block combined with other toy blocks; and,

FIG. 7 is another perspective view thereof, showing the toy block combined with another toy block.

The bottom of the toy block is a mirror image of the top of the toy block.

The rear of the toy block is a mirror image of the front of the toy block.

The right-hand side of the toy block is a mirror image of the left-hand side of the toy block.

FIGS. 1, 6 and 7 are reduced views relative to FIG. 2.

FIG. 5 is an enlarged view relative to FIG. 2.

The broken lines shown are included for the purpose of illustrating unclaimed portions of the article and form no part of the claimed design.
